UNITED STATES PATENT OFFICE.

FRANK M. SELMIER, OF INDIANAPOLIS, INDIANA.

SAFETY TOWEL-HOLDER.

1,172,170.

Specification of Letters Patent. Patented Feb. 15, 1916.

Application filed February 11, 1913. Serial No. 747,618.

To all whom it may concern:

Be it known that I, FRANK M. SELMIER, a citizen of the United States, residing at Indianapolis, in the county of Marion and State of Indiana, have invented certain new and useful Improvements in Safety Towel-Holders, of which the following is a specification.

The object of this invention is to provide a substitute for the unsanitary roller towel in common use in stores, offices and other places where toilet conveniences are supplied to a large number of people, whereby individual towels will be furnished, and a further object of the invention is to prevent the removal of the towels from the place of use while permitting them to be freely and conveniently used one at a time from an original pile of clean towels.

Another object of the invention is to enable the clean towels, suitably perforated, to be threaded on a locking rod and folded and gathered in bundles and counted at the laundry, and tied there in bundles of the required number of towels to a bundle, thereby insuring greater accuracy, convenience and economy in time and labor than where the holding rods are replenished with clean towels where the towels are to be used.

Still another object of the invention is to provide a closed cabinet, with a hinged door for access thereto, within which the clean, folded towels are placed and kept for use, and to which the rod upon which the towels are threaded, is locked so as to prevent the removal of the rod and towels except by an authorized agent having a suitable key, but not so as to prevent the free access to and use of the towels by opening the door of the cabinet.

The above and other objects of the invention which will hereinafter appear, are accomplished by the mechanism illustrated in the accompanying drawings, in which—

Figure 1 is a front view of a cabinet equipped with my invention, the door of the cabinet being shown open. Fig. 2 is a view in transverse vertical section on the line 2—2 of Fig. 1, showing the door closed.

Fig. 3 is an underside view of a portion of the lower shelf of the cabinet with my towel-holding rod secured in operative position to said shelf. Fig. 4 is a front perspective view of a portion of the lower shelf looking up under the latter and showing my improved

towel-holding rod in operative position thereon, no towels being shown, and not showing the padlock by which the rod is locked to the shelf, and Fig. 5 shows the towel-holding rod removed from the cabinet and carrying a bundle of folded towels tied to the rod with a string, as the towels and rod leave the laundry to be delivered to and locked in a cabinet.

Like characters of reference indicate like parts throughout the several views of the drawings.

6 is a cabinet having a top, sides and back immovably connected together, and having a door 7 in front which is hinged to the body of the cabinet for closing the latter and for convenient opening to permit access to the interior of the cabinet.

8 is a shelf which also forms the bottom of the cabinet, and which extends from the cabinet back a suitable distance, but leaving a space between its front edge and the door 7 for the free operation and passage of the towel-holding rod. A shelf 9, of glass or other suitable sanitary material, is conveniently located near the top of the cabinet to receive brush and comb and other toilet articles.

Secured in any suitable permanent way to the front edge of the shelf 8, preferably at the middle of the latter, is a plate 10 having a forwardly projecting lug 11 through which is a transverse hole 12 to receive the bow-shaped bolt of padlock 13, and secured to the rear underside of the shelf 8 is a bolt 14, preferably pressed by a spring 15 into a normal shot position. The lug 11 and bolt 15 are for the purpose of removably securing a towel-holding rod of special shape and construction, which I will now describe, to the shelf 8. This rod comprises a member 16 which occupies a vertical position when assembled in operative position within the cabinet. It is provided with an eye 17 at its lower end, and adjacent thereto is formed with a longitudinal slot or opening to receive the lug 11, and through which the lug 11 is passed and removal prevented by the passing of the bow-shaped bolt of padlock 13 through the opening 12 of said lug. The member 16 extends to within an inch or two of the shelf 9 where it is bent preferably with an inverted U-shaped bend 18, and the rod is then continued downwardly to a distance below the shelf 8, here shown as about 110

the same distance below as the extension is of the member 16 above said shelf and forming the member 19. The extension of the rod above and below shelf 8 is not arbitrary as to distance in either direction. The member 19 terminates with a U-shaped bend 20 and the rod is continued thence upwardly until it reaches the bottom of the shelf 8, forming the member 21 between the bend 20 and shelf 8. The member 19 is shown as being bent about its midlength so as to bring the member 21 in substantially a vertical position as close as practicable to the wall which supports the cabinet, and consequently causing the member 21 to contact with the bottom of the shelf 8 near the rear of the shelf. The rod is then bent forward by a substantially right angled bend and is continued across the bottom of the shelf to form the member 22 which terminates with an eye 23.

The above described rod will preferably be made out of galvanized steel or iron but obviously brass or other materials may be used, and the member 19 will be bent so as to stand to one side of the plane of the member 16, as shown in Fig. 1, so as to provide maximum clearance room between the members 16 and 19 in manipulating the towels 30 and to require the minimum amount of room between the front edge of the shelf and the door 7. The member 22 will be locked to the member 16 by passing the bow-shaped bolt of a padlock 24 through both 35 of the eyes 17 and 23, and obviously, when the ends are locked together in this manner the insertion and removal of towels from the rod is prevented. When the eyes 17 and 23 are unlocked the member 22 by virtue of 40 the torsional strain in member 21 swings with the eye 23 toward the member 19 thereby leaving the lower end of the member 16 unobstructed by the arm 22, which facilitates the removal and replacing of the 45 towels on the rod.

After the rod is bolted to the lug 11 the member 22 is swung up under the underside of the shelf 8 where it is retained by means of the bolt 14, which is passed under it in 50 the manner shown in Figs. 3 and 4.

The towels 26 are suitably perforated at one end and preferably are reinforced with metal gromets 27. The clean towels are secured to the rod, preferably at the laundry, 55 by inserting the eye 17 of member 16 through the gromets of the towels. The towels are folded, either before or after they are strung on the rod, and when the desired number have been thus attached they are 60 tied together in a bundle to prevent displacement in transit from the laundry to the cabinet, by means of a cord 28 which is passed through holes 29 and 30 formed for that purpose, a suitable distance apart, 65 through the member 16. This work of as-

sembling and counting the towels can be more expeditiously and cheaply done by girls at the laundry, than by the man who delivers the towels, for the reason that the wages paid the latter are generally higher 70 and for the further reason that the time which would be consumed by him would mean the correspondingly increased idleness of a delivery horse and wagon which he uses in the transportation of towels to 75 the customer and back to the laundry.

The rod with a bundle of towels tied thereto ready for use, as shown in Fig. 5, is in condition to replace a rod and soiled towels in a cabinet, and in this operation 80 the rod with the soiled towels is unlocked by the removal of the padlock 13 and withdrawal of bolt 14; another rod with the bundle of clean towels is put in its place and there retained by replacing the padlock 85 13, and the bolt 14 is shot under the member 22 of the rod. The bundle of towels is placed upon the shelf 8, as shown in Figs. 1 and 2, and the string 28 is cut and removed leaving the towels free to be separately lifted off of the pile as they are needed for use. This is permitted by the action of the rod through the gromet 27, passing around the loop 18 and bringing the towel in unfolded condition to the position 95 shown on the member 19 in Fig. 1 where it is sufficiently free and accessible for use. After it has been used it is released and dropped down into the loop between the members 19 and 21, where all of the soiled 100 towels are collected and held on the rod.

While I have described my invention with more or less minuteness as regards details of construction and arrangement and as being embodied in certain precise forms, I do not desire to be limited thereto unduly or any more than is pointed out in the claims. On the contrary, I contemplate all proper changes in form, construction and arrangement, the omission of immaterial elements and the substitution of equivalents as circumstances may suggest or necessity render expedient.

I claim:

1. The combination of a support, a rod 115 upon which towels are strung and tied in bundles, said rod having tie-holding releasable means, means connecting the ends of the rod after the towels are strung to prevent their removal from the rod when untied, and means to removably secure the rod to the support, said rod being placed with the towels resting upon said support, said towels before use being untied and released to a portion of the rod from which the 120 towels are to be used.

2. In a towel-holder, the combination of a shelf, a rod upon which towels are strung, the rod being bent to bring its ends in close 125 relation to each other, a lock for removably 130

securing the ends of the rod to each other and means for removably securing the rod to the shelf.

3. In a towel-holder, a cabinet having a shelf, a rod removably locked to said shelf, said rod extending upwardly of the shelf and thence down again, upon which towels are strung, and means for removably locking the ends of the rod together.

10 4. A shelf, a rod locked to said shelf, said rod extending upwardly of the shelf and thence down below the shelf and thence to the place of beginning, means for locking and unlocking the ends of the rod to each other and means comprising a padlock for removably securing the rod to the shelf.

5. A shelf having a perforated lug, a rod having a slot through which the lug passes, 20 a lock to prevent the removal of the rod from the lug, said rod extending upwardly of the shelf and thence outwardly and thence downwardly below the shelf and thence rearwardly and upwardly to the shelf and thence out to the place of beginning, the ends of 25 the rod being perforated, a lock passing

through said perforations to lock the ends together.

6. A cabinet having a shelf, a perforated lug on said shelf, a rod having a perforation 30 to receive said lug, a lock to prevent the withdrawal of the lug from the perforation of the rod, said rod extending upwardly of the shelf, and curved forwardly and then extending downwardly below the shelf and 35 then curved rearwardly and extended upwardly to the bottom of the shelf and then bent outwardly and extended outwardly terminating near the first end of the rod, a bolt to secure the rod under the shelf, the 40 two ends of the rod being perforated, and a lock through the perforated ends of the rod.

In witness whereof I have hereunto set my hand and seal at Indianapolis, Indiana, 45 this 7th day of February, A. D. one thousand nine hundred and thirteen.

FRANK M. SELMIER. [L.S.]
